UNITED STATES PATENT OFFICE

WILLIAM G. POWELL, OF ALTOONA, PENNSYLVANIA

CAR ROOF

Application filed January 6, 1928. Serial No. 244,885.

This invention relates to car roofs of the all-steel riveted-up type wherein self supporting roof sheets extend from side plate to side plate and are riveted thereto and to each other to form a rigid load sustaining structure.

An object of the invention is to improve the structural relation between adjacent roof sheets so as to provide a waterproof joint therebetween by positioning the overlapping portions of the adjacent roof sheets on an incline so as to form a watershed.

Another object is to produce a durable and light weight roof of simple construction which can be easily assembled and cheaply manufactured. The invention consists principally in the improved seam construction hereinafter shown and described; and it also consists in the combinations and arrangements of parts hereinafter described and claimed.

In the drawings:

Fig. 1 is a fragmentary perspective view of a railway car showing my roof applied thereon.

Fig. 2 is an enlarged section on line 2—2 of Fig. 1.

Fig. 3 is a section on line 3—3 of Fig. 2.

Fig. 4 shows a modified form.

In my construction the car roof comprises a plurality of arched or apexed roof sheets 2 which span the distance between the opposite side plates 3 of the car and are preferably secured thereto in any convenient manner.

Each roof sheet is provided with a downwardly inclined oblique portion adjacent one of its longitudinal sides and an upwardly inclined oblique portion 5 adjacent its opposite longitudinal side and the sheets are positioned so that the downwardly inclined portion of one sheet overlaps and is preferably secured to the upwardly inclined portion on the sheet next to it. If desired, some water-proofing material, such as tar paper, may be placed between the sheets before they are riveted together. With this construction any water moving around upon the roof sheet would have to be forced up the inclined surface before it could enter the car.

In the preferred form the underlapping

portion 5 of each sheet is extended to form an integral carline 6 with the roof sheet. This carline spans the distance between the opposite side plates of the car and is secured thereto. In the form illustrated in the drawings I have shown the underlapping portion extended to form a U-shaped carline 6 with its outer margin 7 secured to the body of the adjacent sheet. A carline of this configuration can easily be designed to accommodate any vertical or horizontal loads by varying its depth and width respectively. Furthermore, the carline and its integral roof sheet can easily be pressed between forming dies. Any water which penetrates between the inclined portions of adjacent sheets is caught within the U-shaped carline and not permitted to come in contact with the lading. No drainage is provided for this water because at most it will only be a very small amount and will evaporate within the carline.

Fig. 4 shows a modified form wherein the carline 8 is not integral with a roof sheet but the upwardly inclined portion 5 of the undersheet overlaps the upper portion 9 of the carline so that any water penetrating between the roof sheets enters the valley of the carline and is not permitted to come in contact with or damage the lading.

The body portion 10 of the roof sheet between the upwardly inclined portion on one edge and the downwardly inclined portion on the other edge is inclined toward the integral carline.

The accompanying drawings illustrate the preferred form of the invention, though it is to be understood that the invention is not limited to the exact details of construction shown and described, as it is obvious that various modifications thereof within the scope of the claims will occur to persons skilled in the art.

I claim:

1. A car roof comprising a plurality of roof sheets spanning the distance between the opposite side plates of the car and secured thereto, each of said sheets comprising an inclined body portion having a downwardly inclined oblique portion at one side and an upwardly inclined oblique portion at its opposite side underlapping and secured to the

oblique portion of the adjacent roof sheet.

2. A car roof comprising a plurality of roof sheets spanning the distance between the opposite side plates of the car and secured thereto, each of said sheets having a downwardly inclined oblique portion at one side, and an upwardly inclined oblique portion at its opposite side underlapping and secured to the oblique portion of the adjacent roof sheet, and a carline secured to the lapped portion of adjacent roof sheets and also secured to the opposite side plates.

WILLIAM G. POWELL.
